DRUM

Robert A. Dubois, Marion, Ohio, and Elmer J. Dresher,
North Babylon, N.Y., assignors to Greif Bros. Corporation,
Delaware, Ohio

Filed Feb. 16, 1972, Ser. No. 227,005

Term of patent 14 years

Int. Cl. D9—02

U.S. Cl. D9—170

FIG. 1

FIG. 2

FIG. 3

FIG. 5

FIG. 4

FIG. 1 is a top perspective view of a drum showing our new design;

FIG. 2 is an elevational view;

FIG. 3 is a top plan view;

FIG. 4 is a bottom plan view thereof; and

FIG. 5 is an enlarged fragmentary sectional view taken along the line 5—5 of FIG. 2.

We claim:

The ornamental design for a drum, as shown.
